FREQUENCY MODULATOR

Bernard E. Lenehan, Bloomfield, N. J., assignor
to Westinghouse Electric Corporation, East
Pittsburgh, Pa., a corporation of Pennsylvania

Application December 13, 1946, Serial No. 716,045

13 Claims. (Cl. 332—29)

1

This invention relates to electric discharge apparatus, more particularly to apparatus for producing frequency-modulated oscillations, and it has for an object to provide improved apparatus of this kind.

Apparatus constructed in accordance with the teachings of the prior art, of which I am aware, is exemplified by the Fichandler Patent 2,000,584. Fichandler discloses a system for producing frequency-modulated oscillations comprising an oscillatory circuit or frequency-determining network, across which a variable resistance and a reactance are connected. The components of the network and the resistance and reactance are so set that variation of the resistance over a small range produces variation of the reactance of the whole network without accompanying variation of resistance. Fichandler shows the variable resistance as a three-electrode tube, the grid potential of which is varied to vary the plate resistance.

A transmitter including the Fichandler system has several undesirable features. The output of the transmitter is distorted. It is marred by hum such as arises from undesired pulsations of a 60-cycle power supply and by other sounds not introduced by the modulating source. Amplitude modulations are also at times present in the output.

It is accordingly an object to provide a frequency-modulation system which shall produce signals substantially free of distortion.

Another object is to provide a frequency-modulation system which shall produce signals substantially free of attending current hum.

A further object is to provide a frequency-modulation system in which extraneous sounds are substantially suppressed.

A still further object is to provide a frequency-modulation system which shall produce signals substantially free of amplitude modulation.

It is realized that the sensitive point in a frequency-modulation transmitter is the network at which the modulations are introduced. Beyond this point the frequency multiplication is high. Distortion arising from interelectrode capacity at the modulation network, alternating-current hum, microphonic noises and amplitude modulations introduced at the network are highly amplified by the multiplication effect and materially deteriorate the output.

The interelectrode capacity of Fichandler's resistance tube is substantial, as is also the capacity to ground of the electrodes. These capacities introduce distortion into the modula-

tions impressed on the frequency-determining network. The amplitude of the distortions is small, but the distortions are highly amplified by the frequency multiplication and deteriorate the output of the transmitter.

Fichandler's resistance tube requires a filament supply which is customarily of the rectified alternating-current type. Although this supply is filtered, the filament current retains pulsations of low magnitude. The pulsations, highly amplified, introduce undesirable hum in the output.

The resistance tube has electrodes which have a tendency to vibrate. The sounds which are produced in the ordinary transmitting station and, in particular, in the vicinity of an ordinary communication equipment (aboard a plane or ship or in a police car) tend to cause the electrodes to execute vibrations of minute amplitude. The output of the modulator is highly amplified, and the minute vibrations are converted into substantial microphonic sounds.

In Fichandler's system energy from the oscillation generator flows back with facility to the modulating network. The variable resistance tube (34, Fig. 5), having substantial anode-grid capacity, provides a relatively low impedance feedback path. The regeneration effect produced by the feedback amplified by multiplication also deteriorates the output.

The prior art is further exemplified by the Idzerda Patent 1,648,402. Idzerda makes use of the principle that resistance variation in high-frequency oscillatory circuits causes frequency variation. To obtain this, a microphone is arranged in an oscillator circuit in such manner that the resistance variations caused by the sound waves in the microphone give rise to frequency-variations. The arrangement disclosed in this patent is satisfactory, that is, with the microphone connected directly across the frequency-determining network, as shown; however, if it is desired to modulate the circuit from a point remote from the oscillatory circuit, this arrangement fails to produce modulation because the resistance variations of the microphone are lost in the capacitance of the wires connecting the microphone to the oscillatory circuit.

In accordance with my invention, I provide a frequency-modulating system for a frequency range such as used in carrier-current communications wherein this objection is eliminated by providing a fixed resistance and a rectifier having a non-linear impedance characteristic in

a network connecting a microphone in the oscillatory circuit of a transmitter. The general type of rectifier used is commonly referred to as the barrier-layer type and includes copper-oxide, copper-sulphide, and selenium rectifiers. The resistance of this type of rectifier varies inversely as the current through the rectifier varies. This variation in resistance is introduced in a frequency-determining or oscillatory circuit of a transmitter to produce frequency modulation. Accordingly, it is a further object to provide an improved system for frequency-modulating an oscillatory circuit by varying the reactance of the circuit from a point remote from the oscillatory circuit.

These and other objects are effected by my invention as will be apparent from the following description and claims taken in accordance with the accompanying drawing forming a part of this application, in which:

Figure 1 is a diagrammatic view showing a frequency-modulating system in accordance with my invention;

Fig. 2 is a fragmentary diagrammatic view showing a modification; and,

Fig. 3 is a fragmentary diagrammatic view showing still another modification of my invention.

Referring to the drawing in detail, I show, in Fig. 1, a generator of electrical oscillations such as used in some conventional transmitters comprising an oscillatory circuit or frequency-determining network 10, and a discharge device 11. The discharge device has an anode 12, a cathode 13 and a grid 14. The oscillatory circuit or frequency-determining network 10 comprises condensers 15, 16, 17 and 18 connected in series, and a variable inductance 19 connected in parallel with said condensers. The circuit is adjusted to resonate at different frequencies by varying the inductance 19. Anode potential is supplied to the discharge device 11 from a source (not shown) through an RF choke 20. Feedback energy from the anode 12 to the grid 14 to maintain the circuit 10 in oscillation is accomplished through a condenser 21. The grid 14 is properly biased with respect to the cathode through a resistance 22.

The frequency at which the generator will oscillate is determined by the reactance of the circuit 10. The oscillation generator may be frequency-modulated by varying the reactance of the circuit 10 in the proper manner. It is a purpose of this invention to frequency-modulate the generator from a point remote from the circuit 10. To accomplish this, I utilize a network comprising a full-wave rectifier 25, a resistance 26, an audio transformer 27 having a primary winding 28 and a secondary winding 29, and a microphone 30 located at some position remote from the frequency-determining network or oscillatory circuit 10.

The rectifier 25 comprises four metallic units 31 of the type previously described herein, connected in a bridge to provide full-wave rectification. As previously stated, the resistance of this type rectifier unit varies inversely as the current through it varies. The input or alternating-current side of the rectifier 25 is connected across the condenser 16 of the frequency-determining network or oscillatory circuit 10 by two long conductors 32 and 33. The resistance 26 and the secondary winding 29 of the transformer 27 are serially connected across the output or direct-current side of the rectifier bridge 25. The primary winding 28, the microphone 30, and a poten-

tial source 35 are serially connected on the primary side of the transformer 27. A condenser 36 is shunted across the secondary 29 of the audio transformer to bypass the second harmonic of the carrier frequency.

When the circuit 10 is oscillating unmodulated, a substantially constant radio frequency potential of approximately 3 volts appears across the condenser 16. This potential is rectified by the rectifier 25 and applied across the resistor 26 and the secondary winding 29 of the transformer 27. This potential causes a definite value of direct current to flow in the resistor 26. However, when an audio frequency or modulating potential is applied to the primary winding 28, by speaking into or otherwise varying the resistance of the microphone 30, this audio potential will also appear across the resistor 26 and the secondary winding 29 in series with the rectified radio frequency potential. Consequently, any variation in the audio frequency or modulating potential causes a corresponding variation in the direct current flowing in the resistance 26. As stated hereinbefore, the resistance of the rectifier 25 varies as the current flowing through it varies, therefore, a variation of the direct current in the resistance 26 causes a variation in the resistance on the alternating-current or input side of the rectifier 25. For example, when the top of the secondary winding 29 is negative, the total current flowing in the resistance 26 may be zero. Then the resistance on the alternating-current or input side of the rectifier bridge 25 would be high. Accordingly, if the upper end of the winding 29 should be positive, the total current flowing in the resistance 26 would be high, and the resistance across the alternating-current or input side of the rectifier bridge 25 would be low. From these illustrations, it is seen that the resistance across the alternating-current or input side of the rectifier bridge 25 varies inversely as the current through the resistance 26 varies. Since the rectifier bridge 25 is in parallel with the condenser 16 of the frequency-determining or oscillatory circuit 10, any variation of the resistance of the rectifier bridge 25 will vary the reactance of the circuit 10 and cause it to oscillate at a different frequency. Thus it is seen that the oscillation generator is frequency-modulated as the current flowing through the resistance 26 and rectifier 25 varies.

The output may be taken from the frequency-determining or oscillatory circuit 10 in any convenient manner. For the purpose of illustration, I have shown a push-pull amplifier connected across the circuit 10 by conductors 40 and 41. The conductor 40 is connected to the grid 42 of an amplifier tube 43 and the conductor 41 is connected to the grid 44 of an amplifier tube 45. The anodes 46 and 47 of these tubes are connected in push-pull through the primary of a transformer 50. A positive potential is applied to the anodes from a suitable source (not shown) at the center point of the primary of the transformer 50. The cathodes 48 and 49 of the amplifier tubes are grounded at 51. A suitable load, such as another stage of amplification or a radiating antenna, may be connected to the output terminals 52 of the secondary of the transformer 50.

Fig. 2 illustrates an embodiment of my invention using two rectifier units instead of four to obtain full-wave rectification of the radio frequency voltage appearing across the inductance 19. In this embodiment, the variable resistance effecting frequency modulation of the frequency-

determining or oscillating circuit 10 is in parallel with the inductance 19 instead of in parallel with the condenser 16 as in the previous embodiment. In this embodiment, the condenser 16 is made variable for adjusting the circuit 10 for resonance. In all other respects this embodiment is identical in construction and operation to the previous embodiment.

Fig. 3 illustrates an embodiment of my invention using a single rectifier unit 31. In all other respects this embodiment is identical in construction and operation to the embodiment illustrated in Fig. 1.

In Figs. 2 and 3 arrows indicate connections to the anode 12, cathode 13, and grid 14 of the discharge device 11.

From the foregoing description it is seen that I have provided a simple and efficient method of frequency-modulating an oscillatory circuit from a remote point to produce signals substantially free of distortion, alternating-current hum, extraneous noises, and amplitude noises.

While I have shown my invention in several forms, it will be obvious to those skilled in the art that it is not so limited but is susceptible of various other changes and modifications without departing from the spirit thereof, and I desire, therefore, that only such limitations shall be placed thereupon as are specifically set forth in the appended claims.

I claim as my invention:

1. In combination, a generator of electrical oscillation comprising a frequency-determining network, a source of audio frequency for modulating said generator, means connecting between said audio source and said generator comprising a network shunting said frequency-determining network and including a full wave rectifier the resistance of which varies as the current therethrough varies, and means remotely of said generator for causing the current flowing through said rectifier to vary.

2. In combination, a generator of electrical oscillations including a frequency-determining network, means for effecting frequency modulation of said oscillations comprising a full wave rectifier connected in shunt with said frequency-determining network, a source of modulating frequency connected to said rectifier, and a resistance connected in series with said modulating source and said rectifier.

3. In combination, a generator of electrical oscillations including a frequency-determining network, means for effecting frequency modulation of said oscillations comprising a barrier-layer rectifier connected in shunt with said frequency-determining network, a source of modulating frequency connected to said rectifier, and a resistance connected in series with said modulating source and said rectifier.

4. In combination, a generator of electrical oscillations including a frequency-determining network comprising a four terminal full wave rectifier having two of its terminals connected in shunt with said frequency-determining network, a source of modulating frequency connected to the other two terminals of said rectifier, and a resistance in series with said modulating source.

5. In apparatus including a frequency determining network for providing a frequency modulated output voltage, the combination of a first voltage source, said first voltage being proportional to said output voltage, a variable impedance including a rectifier network having an in-

put circuit and an output circuit, a fixed impedance, said input circuit being connected in shunt across said first voltage source and said output circuit being connected to apply a first direct current voltage across said fixed impedance, and a modulating voltage source connected in series with said output circuit and said fixed impedance to apply a second direct current voltage across said fixed impedance.

6. The combination as claimed in claim 5, in which the rectifier network comprises a full wave rectifier.

7. In apparatus for providing a frequency modulated output voltage, the combination of a source of alternating current voltage which is proportional to said output voltage, a resistance member, a full wave rectifier network connected between said alternating current voltage source and said resistance member and adapted for applying a first direct current voltage across said resistance member, a source of a modulating voltage, and connections for applying a second direct current voltage across said resistance member proportional to said modulating voltage.

8. In apparatus for providing a frequency modulated output voltage, the combination of an alternating current voltage source, said alternating current voltage being proportional to said output voltage, a variable impedance comprising a full

30 wave rectifier network having an input circuit and an output circuit, said input circuit being connected across said alternating current voltage source, a fixed impedance connected to said output circuit such that a first direct current voltage 35 is applied across said fixed impedance, a modulating voltage source, and connections between said modulating voltage source and said fixed impedance such that a second direct current voltage is applied across said fixed impedance.

9. The combination as claimed in claim 8, with the second direct current voltage being applied across the fixed impedance in a direction such that a resultant direct current voltage occurs which has a magnitude that determines the effective frequency modulation of said output voltage.

10. In apparatus including a frequency determining network for providing a frequency modulated output voltage, the combination of a first voltage source, said first voltage being proportional to said output voltage from said frequency determining network, a variable impedance comprising a rectifier network having an input circuit and an output circuit, said input circuit being connected in shunt across said first voltage source, a second impedance connected to said output circuit such that a first current is established in said second impedance, and a modulating voltage source connected in series with said second impedance and said output circuit to establish a second current in said second impedance.

11. In apparatus including a frequency determining network comprising a tuned capacitance and inductance circuit for providing a frequency modulated output voltage, the combination of a first voltage source comprising a portion of said frequency determining network, a variable impedance comprising a rectifier having an input and an output, said input being connected in shunt across said first voltage source, a second impedance connected to said rectifier output such that a first current level is established in said second impedance which is proportional to said output voltage, and a source of modulating voltage connected in series to said second impedance

and said rectifier output such that a second current level is thereby established in said second impedance to determine the modulation of said output voltage.

12. In apparatus for providing a frequency modulated output voltage, the combination of a first voltage source, said first voltage being proportional to said output voltage, a variable impedance including a full wave rectifier network having an input circuit and an output circuit, said input circuit being connected in shunt across said first voltage source, a modulating voltage source, and a fixed impedance member connected in series between said output circuit and said modulating voltage source.

13. In apparatus for providing a frequency modulated output voltage, the combination of a source of a first voltage which is proportional to said output voltage, an impedance member, a full wave rectifier network connected between said first voltage source and said impedance member, a second source of voltage, and connections from said second voltage source to said impedance member.
